UNITED STATES PATENT OFFICE

SAMUEL A. NELSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

WEFT-REPLENISHING MECHANISM FOR PICKS AND PICK LOOMS

Application filed August 1, 1928. Serial No. 296,732.

This invention relates to an improved weft replenishing mechanism particularly adapted for use on a pick and pick loom.

It is the general object of my invention to provide improved mechanism by which any desired weft carrier or bobbin may be released and transferred on the pick following indication and without changing or delaying the operation of the regular picking mechanism of the loom.

A further object is to provide mechanism by which the transfer is effected in two steps or stages and in which the latter stage of the transfer may be effected during the shifting movement of the boxes.

To the attainment of this object, I provide an intermediate receiver or carrier which receives the indicated weft carrier while the shuttle is in flight and thereafter delivers the weft carrier to the shuttle at front center, said receiver or carrier being movable vertically with the shuttle boxes and being at all times horizontally aligned therewith.

My invention further relates to arrangements and combinations of parts which will be hereinafter described and more particularly pointed out in the appended claims.

A preferred form of the invention is shown in the drawings in which

Fig. 1 is a side elevation of a loom embodying my improvements;

Fig. 2 is a detail plan view, looking in the direction of the arrow *a* in Fig. 1;

Fig. 3 is a bottom view, looking in the direction of the arrow *b* in Fig. 2;

Fig. 4 is a plan view of portions of a magazine, looking in the direction of the arrow *c* in Fig. 1;

Fig. 5 is a front elevation of parts of the magazine mechanism, looking in the direction of the arrow *d* in Fig. 4;

Fig. 6 is a sectional plan view of the magazine and associated parts, taken along the line *e*—*e* in Fig. 1;

Figs. 7 and 8 are detail sectional front elevations, taken along the lines *f*—*f* and *g*—*g* in Fig. 6;

Fig. 9 is a front elevation of the intermediate bobbin receiver or carrier;

Fig. 10 is a sectional plan view thereof, taken along the line *h*—*h* in Fig. 9;

Fig. 11 is a plan view of certain parts of the carrier, to be described;

Fig. 12 is an enlarged side elevation of certain actuating connections;

Fig. 13 is a sectional side elevation thereof;

Figs. 14 and 15 are transverse sectional elevations, taken along the lines *i*—*i* and *j*—*j* in Fig. 12;

Fig. 16 is a sectional end elevation, taken along the line *k*—*k* in Fig. 13;

Figs. 17, 18 and 19 are sectional plan views of the intermediate receiver or carrier and illustrate successive stages in the transfer operation;

Fig. 20 is a perspective view of a weft carrier holder to be described.

Referring particularly to Fig. 1, I have indicated parts of a pick and pick loom comprising a loom frame 30, a magazine *M*, a plurality of drop boxes 31 mounted on the usual lifter rod 32 and a bottom or cam shaft 33 which, as usual, makes one revolution for every two picks of the loom.

Magazine mechanism

The magazine is of the multi-color stationary type and is in general substantially similar to the magazine shown in the prior patent to Wyman, No. 970,591, issued September 20, 1910.

I have shown the magazine *M* as provided with three vertical compartments 35 (Fig. 4) but it should be understood that my invention is not limited to a particular number of compartments and that either more or less compartments may be used as desired, the number of compartments commonly corresponding to the number of shuttles used in the loom.

The weft carriers in each compartment are supported on rocking cradles (not shown) and are selectively released upon indication of transfer.

A shaft 36 (Figs. 1 and 4) is slidably mounted in bearings on the magazine *M* and is provided with a grooved collar 37 (Fig. 1) engaged by a fork at the upper 100

end of a bell crank 38 pivoted at 39 on the loom frame and connected by a cord or other device 40 to the pattern mechanism of the loom, so that the longitudinal position 5 of the rod 36 will always correspond to the shuttle about to become active.

A finger 42 (Fig. 4) is fixed on the rod 36 and is moved with the rod 36 into position to co-operate with one of a series of 10 slide bars 44 by which the cradles are rocked. The rod 36 and finger 42 are collectively termed the "color slide."

An arm 46 (Fig. 4) forms an extension of the part 42 and is provided with an offset 15 portion 47 extending parallel to the rod 36 and seated in a notch 48 (Fig. 5) in an arm 49 loosely pivoted on the rod 36 and movable by a connection 50 upon indication of transfer.

20 For a more complete description of the operation of the magazine, reference is made to the patent to Wyman above cited.

The connector 50 (Fig. 1) is pivoted at its lower end to an arm 51 swinging about a 25 fixed pivot 52 and having an upwardly extending portion 53 which has a pin and slot connection with an arm 54 on the usual indicator rod 55. The rod 55 extends along the breast beam to the opposite side of the 30 loom and receives a rocking movement upon indication of weft exhaustion by the detecting mechanism, not shown.

Detecting mechanism for pick and pick 35 looms is well known and any such suitable mechanism may be utilized for rocking the shaft 55 upon indication of weft exhaustion, the detecting mechanism and the actuating mechanism for the shaft 55 forming no part 40 of my present invention and being well known in the art.

Transfer mechanism

As the bobbin is released from a selected 45 compartment of the magazine, it falls upon fixed guide-ways 60 and 61 (Fig. 6) formed on a frame or support 62 for a transfer member 63. Said transfer member is slideable in dovetailed guide-ways 64 in the stand 62 and is provided with an end portion 65 to engage the butt of the bobbin and with an end portion 66 spaced therefrom and adapted to engage the tip of the bobbin B.

55 A bracket 68 (Fig. 7) is clamped to the transfer member 63 and is provided with a stud 69 extending through a slot 70 in the upper end of an actuating lever 71 (Fig. 1) mounted on a fixed pivot 72 and having a pin and slot connection at its lower end with an actuating rod 73. The rod 73 is detachably connected with a rod 74, substantially aligned therewith and pivoted at its rear end to a cam lever 75 (Fig. 1) swinging about a fixed pivot 76 and having a roll

seated in the cam groove 78 of a cam 79, mounted on the cam shaft 33 previously described.

Actuating connector and control

The connections between the rods 73 and 74 are best shown in Figs. 12 to 16. The rod 73 is threaded in a sleeve 80, slideable in a bearing 81 formed on a bracket 82 fixed to the loom side 30.

The sleeve 80 has an adjusting or stop screw 84, engaging the end of the bearing 81 and thus determining the rearward position of the rod 73. A spring 85 is connected to an arm 86 mounted on the rod 73 and acts to hold the rod and sleeve yielding in rearward position.

The sleeve 80 receives the forward end of the rod 74 in a recess 87 (Fig. 13) and a screw 88 in the sleeve extends into a longitudinal recess or key-way 89 in the rod 74, preventing angular movement thereof and limiting longitudinal separation of the rod 74 and sleeve 80.

The rod 74 is regularly reciprocated by 90 the cam 78 but commonly slides freely in the recess 87 of the sleeve 80. A stud 90 is mounted in a transverse bearing 91 in the sleeve 80 and is normally held out of the path of the rod 74 by a spring 92 engaging a 95 collar 93 on the stud 90.

The front end of the rod 74 is provided with a shoulder 94 (Fig. 13) and the lower end of the stud 90 is provided with a head 95, adapted to be caught under the shoulder 100 94 when the stud is depressed into the recess 87.

When the stud is depressed and caught by the shoulder 94, it forms a rigid connection between the rod 74 and the sleeve 80, and thus causes motion to be transmitted to the actuating lever 71.

A rocker arm 96 (Fig. 14) is pivoted at 97 on the fixed bearing 81 and has a longitudinally extended end portion 98 engaging the upper end of the stud 90 in every longitudinal position of the sleeve 80.

The rocker arm 96 is connected to a wire or cord 99 (Fig. 1) which extends around a guide pulley 100 and is connected to a 115 downwardly extending arm 101 pivoted at 52 and movable with the arms 51 and 53 previously described.

Upon indication of weft exhaustion, all 120 of said arms are moved in a clockwise direction, as viewed in Fig. 1, and the connector 99 is thus pulled upward, rocking the arm 96, and depressing the stud 90 to render the rod 74 operative.

Intermediate receiver or carrier

The intermediate receiver or carrier 110 (Fig. 9) constitutes one of the outstanding features of my present invention. This carrier 110 is mounted in vertical guideways 130

111 and 112 forming parts of a fixed bracket 113 (Fig. 1) secured to the loom frame 30.

The carrier 110 is provided with three vertically spaced horizontal guideways 114, in which are slidably mounted members 115 (Fig. 20) which project rearward and form supports for bobbin holding springs 116. Each member or slide 115 is provided with two recesses 117 (Fig. 10) along one edge thereof, positioned for engagement by a spring plunger 118, slidably mounted in the frame of the carrier 110. When the plunger is seated in either one of the recesses 116, it yieldingly resists displacement of the slide 115.

A bunter 115^a is mounted on the inner end of the slide 115 and is engaged by some portion of the drop box 31 as the lay moves forward when the slide 115 is in rearward position. The cooperative effect of these parts during transfer will be hereinafter described.

The carrier 110 is supported on an auxiliary lifter rod 120 (Fig. 9), which is connected at its lower end, as indicated at 121 in Fig. 1, for vertical movement simultaneously with movement of the drop box lifter rod 32. The connection is such that as the lay swings toward or away from front center, the bobbin holding springs 116 will be moved vertically in unison with the drop boxes and will be held substantially in horizontal alignment therewith.

Whenever a weft carrier is to be transferred, the slide 115 and spring 116 corresponding to the active shuttle is moved rearward a short distance. For this purpose I provide a lever 122 (Figs. 6 and 8) having an upwardly and rearwardly projecting end portion 123 adapted to engage the slide 115 corresponding to the active shuttle. This lever 122 is pivoted at 124 and has a pin and slot connection to a second lever 125 pivoted at 126 and supporting a cross stud 127 having a laterally extended head 128 (Figs. 6 and 8).

The head 128 is positioned for engagement by the upper end of the actuating lever 71 as said lever swings rearward to move the transfer member 63. When the lever 71 engages the head 128, it rocks the levers 125 and 122 and causes the end 123 of the lever 122 to push the corresponding slide 115 quickly rearward, shifting the spring plunger 118 to the forward recess 117.

Springs 129 (Fig. 8) on the studs 124 and 126 act to yieldingly maintain the levers in the inoperative position indicated in full lines in Fig. 6.

Auxiliary transfer member

The intermediate carrier 110 is provided with an auxiliary transfer member 130 (Figs. 9 to 11) supported on two plungers 131 slidably axially in bearings in the car-

rier 110 and provided with springs 132 pressing the plungers 131 and auxiliary member 130 yieldingly to the left in Fig. 9. The left hand ends of the plungers 131 are seated in bosses on a head plate 133 positioned for engagement by the upper end of a lever 134 (Fig. 9) pivoted at 135 (Fig. 1) and having a depending portion 136 offset at its lower end, as indicated at 137 in Fig. 2, and provided with a roll 138 engaged by a cam plate 139 mounted on the rod 73 previously described.

The cam plate 139 is normally positioned as indicated in Fig. 2, pressing the cam roll 138 outward, and causing the lever 134 to hold the auxiliary transfer member 130 in the operative position shown in Figs. 9 and 10.

Upon indication of transfer, however, the rod 73 moves forward, carrying with it the cam 139 and permitting the springs 132 to withdraw the head 130 to the position indicated in Fig. 17. When in this position, a bobbin B may be pushed freely rearward past the member 130 until it is grasped by one of the pairs of springs 116.

The member 130 is provided with three pairs of spaced projections 140 which help to guide the bobbins in their rearward travel.

Operation

Having described the details of construction of my improved weft replenishing mechanism, the method of operation thereof is as follows:

Upon indication of transfer, one of the cradles in the magazine is rocked to release a weft carrier and to allow it to fall on to the supporting surfaces 60 and 61 (Fig. 6) in the path of the transfer member 63. At the same time the cord 99 (Fig. 1) is pulled upward to depress the stud 90 (Fig. 13) and thus render the actuating lever 71 operative. The lever 134 (Fig. 9) is simultaneously withdrawn, permitting the member 130 to move to inoperative position.

The released bobbin is then pushed rearward by the transfer member 63 until it enters between one of the pairs of spring jaws 116, which jaws are moved further rearward by the action of the levers 125 and 122 (Fig. 6).

This completes the first stage of the transfer; the spring jaws 116 and the slide 115 being yieldingly held in rearward position by one of the spring plungers 118, as indicated in Fig. 18, and these operations being completed as the loom passes back center.

The plunger 73 then returns to its rearward position, actuating the lever 134 to move the member 130 to the right and in front of the butt of the bobbin, as indicated in Fig. 18. As the lay comes forward, the 130

bobbin B is held in rearward position by the member 130 and engages the exhausted weft carrier B' (Fig. 19) forcing the same rearward out of the shuttle S, the bobbin B being simultaneously inserted in the shuttle and the transfer being thus completed.

During this same forward movement of the lay, the bunter 115^a on the slide 115 is engaged by the forwardly moving drop boxes 31 and is pushed forward, the bobbin-holding spring jaws 116 passing over and under the member 130. This action removes the slide 115 and spring jaws 116 from the path of the forwardly moving shuttle, while the new bobbin is held from substantial forward movement by its engagement with the member 130. The engagement of the drop boxes 31 with the bunter 115^a also has the effect of resetting the slide 115 in normal forward position.

As the intermediate receiver or carrier 110 is mounted to move vertically with the drop boxes, it will be seen that the second stage of the transfer may be carried out, regardless of the vertical position of the boxes, and in fact during the vertical shifting of the boxes, as the bobbin to be transferred is held continuously in horizontal alignment with the shuttle which is to receive the bobbin.

I am thus able to complete the transfer on the same pick on which the indicated shuttle is received at the magazine side of the loom, and this transfer will be satisfactorily completed whether or not the indicated shuttle remains active for the ensuing pick, and with no alteration in the speed of operation of the loom.

Having thus described my invention and the advantages thereof, I do not wish to be limited to the details herein disclosed, otherwise than as set forth in the claims, but what I claim is:—

1. In a weft replenishing loom, a plurality of shifting shuttle boxes, a multi-color magazine associated therewith, means to release a selected weft carrier therefrom corresponding to the shuttle about to be picked to the magazine side of the loom, means to move said weft carrier rearward to an intermediate position as said shuttle is boxed, and fixed means to resist forward movement of said weft carrier from said intermediate position when engaged by a substantially exhausted weft carrier in a boxed shuttle thereby causing rearward ejection thereof.

2. In a weft replenishing loom, a plurality of shifting shuttle boxes adapted to receive shuttles open at their front and rear sides, means to advance a selected weft carrier to a position in the path of a shuttle approaching front center, and means to hold such weft carrier from forward move-

ment and in fixed position when engaged by a weft carrier in said shuttle.

3. In a weft replenishing loom, a plurality of shifting shuttle boxes adapted to receive shuttles open at their front and rear sides, a transfer member by which a selected weft carrier is moved rearward to an intermediate position, an auxiliary transfer member, means to move said auxiliary member from operative position while said weft carrier is moved rearward, and means to thereafter restore said auxiliary member to a fixed position to resist forward movement of said weft carrier when engaged by a weft carrier in the shuttle to be replenished.

4. In a weft replenishing loom, an intermediate bobbin receiving device normally positioned forward of the path of shuttle movement, means to insert a bobbin in said device upon indication of weft exhaustion and to move said device rearward into the path of shuttle movement, and means to thereafter and hold said bobbin in substantially fixed position and prevent forward movement of said bobbin when said bobbin is engaged by a substantially exhausted bobbin in a forwardly moving shuttle.

5. In a weft replenishing loom, an intermediate bobbin receiving device, a transerrer, means for moving said transerrer rearward to insert a bobbin in said device upon indication of weft exhaustion, and additional means rendered operative as said transerrer moves rearward and effective to move said bobbin receiving device rearward into the path of a forwardly moving shuttle.

6. In a weft replenishing loom, an intermediary bobbin receiving device normally positioned forward of the path of shuttle movement, means to insert a bobbin in said device upon indication of weft exhaustion and to move said device rearward into the path of shuttle movement, means to hold said bobbin in substantially fixed rearward position when engaged by a substantially exhausted bobbin in a forwardly moving shuttle, and means to reset said bobbin receiving device in normal forward position.

7. In a weft replenishing loom, an intermediate bobbin receiving device normally positioned forward of the path of shuttle movement, means to insert a bobbin in said device upon indication of weft exhaustion and to move said device rearward into the path of shuttle movement, means to hold said bobbin in substantially fixed rearward position when engaged by a substantially exhausted bobbin in a forwardly moving shuttle, and means to move said bobbin receiving device forward to release the fresh bobbin for transfer, while thus holding said bobbin in fixed rearward position.

8. In a weft replenishing loom, a lay, a magazine, an intermediate slide having bobbin holding spring jaws, means to insert a

fresh bobbin in said slide and to move said slide rearward upon indication of weft exhaustion, a member adapted to be thereafter moved to a fixed position forward of said bobbin and effective to prevent substantial forward movement of said bobbin, and means engaged by said lay effective to move said slide forward while said bobbin is held by said member from forward movement.

9. In a weft replenishing loom, a lay, a magazine, an intermediate slide having bobbin holding spring jaws, means to insert a fresh bobbin in said slide and to move said slide rearward upon indication of weft exhaustion, a member adapted to be thereafter positioned forward of said bobbin and effective to prevent substantial forward movement of said bobbin, and means engaged by said lay effective to move said slide forward while said bobbin is held from forward movement, said jaws passing above and below said member and supporting the fresh bobbin until grasped by the shuttle springs.

10. In a weft replenishing loom, a magazine, a plurality of shifting shuttle boxes at the magazine end of the loom, an intermediate weft carrier receiver, means to transfer a selected weft carrier from said magazine to said receiver, means to move said weft carrier and receiver rearward to place said weft carrier in the path of movement of the active shuttle, an auxiliary transfer member, and means to move said member axially of the weft carrier after the rearward movement of said carrier and into a position directly in front of said carrier, whereby said weft carrier is held from forward movement and ejects the weft carrier in the active shuttle by direct engagement therewith.

40 In testimony whereof I have hereunto affixed my signature.

SAMUEL A. NELSON.
